(57) **CLAIM**

I claim the ornamental design for a hood for clothing, as shown and described.

DESCRIPTION

The patent or application file contains at least one drawing/ photograph executed in color. Copies of this patent with color drawing(s)/photograph(s) will be provided by the Office upon request and payment of the necessary fee.

FIG. 1 is a perspective view of a hood for clothing, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The portions of the hood for clothing shown in faded gray and with broken lines form no part of the claimed design.

**1 Claim, 5 Drawing Sheets
